US00D950485S

(12) **United States Design Patent** (10) Patent No.: **US D950,485 S**
Mercer et al. (45) Date of Patent: ** May 3, 2022

(54) **CHARGING STATION**(71) Applicant: **Volta Charging, LLC**, San Francisco, CA (US)(72) Inventors: **Scott A. Mercer**, Pacifica, CA (US); **Alex Prodaniuk**, Pacifica, CA (US); **Stephan Lintner**, Anif-Salzburg (AT); **Julian Schloemer**, Anif-Salzburg (AT); **Marco Wilhelm**, Salzburg (AT)(73) Assignee: **Volta Charging, LLC**, San Francisco, CA (US)(***) Term: **15 Years**(21) Appl. No.: **29/757,238**(22) Filed: **Nov. 4, 2020**(51) LOC (13) Cl. .... **13-02**(52) U.S. Cl. USPC .... **D13/107**(58) **Field of Classification Search**

CLAIM

The ornamental design for a charging station, as shown and described.

DESCRIPTION

FIG. 1 is a front perspective view of a charging station showing our new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The broken lines in the drawings illustrate portions of the charging station that form no part of the claimed design.
